UNITED STATES PATENT OFFICE.

FRED A. SCHLOSSER, OF MANSFIELD, OHIO.

HEATING STOVE OR FURNACE.

No. 837,967.

Specification of Letters Patent.

Patented Dec. 11, 1906.

Application filed February 25, 1904. Serial No. 195,274.

To all whom it may concern:

Be it known that I, FRED A. SCHLOSSER, a citizen of the United States of America, and a resident of Mansfield, Ohio, have invented 5 certain new and useful Improvements in Heating-Stoves or Furnaces, of which the following is a specification.

My invention relates to an improvement in heating stoves or furnaces, the objects being 10 to provide a means for retaining, emitting, and diffusing the heat-waves of such heating apparatus into a room or apartment in such a manner as to obtain a higher efficiency of radiation than can be accomplished by the 15 use of an ordinary heating apparatus; and to this end I provide a construction wherein the heat generated by the fuel is caused to take a more circuitous route within flues of a peculiar design to permit the products of combustion 20 to communicate their heat to the flues.

My invention is therefore designed to provide a means for constructing a heat-radiator composed of one or more series of flat tubes or flues intended to be combined with flue- 25 heads and hoods of novel construction, which latter are applied to any suitable heating apparatus.

I attain the foregoing and other objects by means of the construction hereinafter set 30 forth and particularly pointed out in the claims.

In the accompanying drawings, Figure 1 is a view in front elevation of my improved stove constructed to use coal or other fuel 35 than gas. Fig. 2 is a view in side elevation of Fig. 1. Fig. 3 is a top plan view of a flue-head designed to connect the flues in series. Fig. 4 is a vertical cross-sectional view of Fig. 1, taken on the line xx . Fig. 5 is a view in rear 40 elevation of the construction shown in Fig. 1. Fig. 6 is a top plan view of a hood adapted to receive the products of combustion from the lower ends of the rear series of flues shown in Fig. 4. Fig. 7 is a detail view in side and end 45 elevation of one of the radiating-flues. Figs. 8 and 9 are views in front and side elevation, respectively, showing a slightly-modified form of means for connecting the radiating-flues to the hood; and Fig. 10 is a top plan 50 view of a flue-head for connecting the flues in single series.

A indicates a suitably-supported heating-stove provided with the usual fire-box, superposed upon which is the elongated flame-

chamber *a*, constituting a portion of the 55 stove proper and being provided with the rim *1*, received within which rim is the flange *2* of a flue-head *b*. This flue-head is provided with a ledge *b'*, which projects transversely from the flange *2* and serves as a stop 60 against which the rim *1* of the flame-chamber is received. The head is also provided with a series of apertures surrounded by collars *c*, such as shown in Fig. 10, adapted to receive and fit within the lower ends of a series of 65 flattened flues *e e*, the upper ends of the flues adapted to support an upper flue-head *d*, provided with a series of apertures and collars *4*, similar to those on the flue-head *b*, for receiving the upper ends of the flues and having a 70 rim *3* for the reception of a hood *f*, the upper flue-head provided with a flange *5*, forming a seat, against which the edges of the hood abut.

In the form of stove shown in Figs. 1, 2, 4, and 5 I provide a double series of flues and 75 flue-openings in each flue-head, a single hood *f*, adapted to connect the upper ends of the opposing flues with one another.

Forming a part of the stove is the smoke-hood *g*, which hood is suitably supported 80 upon the body of the stove by means of the shoulder *6* and lug *7*, the hood provided with an opening *8* to afford direct communication with the fire-box to permit of a draft, the opening being controlled by means of a damper *9*. The lower hood or smoke-hood is 85 open at its top to afford free communication with the rear series of flues *e'*, connecting the upper and lower hoods, and a smoke-outlet *g'* to the chimney or other suitable place is provided. 90

The rear series *e'* of flues are supported upon a flue-head *10*, mounted upon the smoke-hood *g*, the flue-head provided with a guard edge *11*, which passes around the stove-body 95 and having an extension *12*, inclosing or embracing the smoke-outlet *g'* to protect the latter against injury. The guard-ledge also serves to retain the flue-head in position.

The form of upper flue-head *d* employed 100 with the double series *e e'* of flues is shown in detail in Fig. 3.

It will be observed that the products of combustion pass up through the flues *e* in the direction of the arrow, through the hood *d*, 105 thence downward through flues *e'*, as shown by the arrow, into the smoke-hood *g*, and thence through the outlet *g'*.

When it is desirable to start the fire or to cause it to burn more freely, the damper 9 is opened to permit of a direct passage of the products of combustion from the flame-chamber into the smoke-hood and thence up the chimney.

Figs. 8 and 9 show separate hoods 21 for connecting the uptake and downtake flues *e* and *e'* independently of each other.

10 It will be observed that by the construction of my device the heat products are caused to follow a circuitous route, during which the heat is imparted to the metallic flues and hoods, which radiate it into the 15 room or apartment wherein the heater is situated. It will also be evident that changes might be made in the form and arrangement of the several parts described without departing from the spirit and scope 20 of my invention, and hence I do not wish to limit myself to the exact construction herein shown; but,

Having thus fully disclosed my invention, what I claim as new, and desire to secure by 25 Letters Patent, is—

1. In a stove, the combination with a combustion-chamber, of a laterally-extending smoke-chamber in direct communication with the combustion-chamber, the smoke-chamber provided with a smoke-outlet, means for controlling the communication between the smoke-chamber and the combustion-chamber, a series of uptake-flues in direct communication with the combustion-chamber, a series of downtake-flues directly connected with the smoke-chamber at their lower ends, and means for connecting the upper free ends of the uptake and downtake flues, the products of combustion passing 40 entirely through the uptake and downtake flues or directly to the smoke-outlet through the smoke-chamber irrespective of the uptake and downtake flues.

2. The combination with a stove-body 45 having a combustion-chamber, of a laterally-extending smoke-chamber, a shoulder on the stove-body for supporting the smoke-chamber laterally of the combustion-chamber, a direct communication between the combustion and the smoke chambers, the latter provided with an outlet, means for controlling this direct communication, and uptake and downtake flues mounted upon the combustion and smoke chambers, respectively, for affording an indirect communication between the combustion-chamber and the smoke-chamber, the products of combustion passing entirely through both uptake and downtake flues or else directly 60 through the smoke-chamber irrespective of the flues.

3. The combination with a stove provided with a combustion-chamber, a flame-cham-

ber removably mounted thereupon, a smoke-chamber mounted laterally of the combustion-chamber and on a plane beneath the flame-chamber, the flame-chamber rising above the smoke-chamber, a series of short uptake-flues mounted upon the flame-chamber, a series of longer downtake-flues mounted upon the smoke-chamber, and means for connecting the upper ends of the flues, the products of combustion passing up through the uptake-flues and down through the entire length of the downtake-flues and into the 75 smoke-chamber before escaping from the stove.

4. The combination with a stove having a removable flame-chamber, of a flue-head, the flue-head provided with a flange receivable 80 upon the flame-chamber, a ledge projecting laterally of the flue-head against which ledge the edge of the flame-chamber engages, the flue-head further provided with a series of apertures, collars surrounding the apertures, 85 a series of uptake-flues removably mounted on the collars and inclosing the apertures, a smoke-chamber, a flue-head mounted thereon, a series of downtake-flues mounted upon the flue-head and means for connecting the 90 upper ends of the flues.

5. The combination with a stove, provided with a removable flame-chamber, an apertured flue-head mounted directly above the fire-chamber, a smoke-chamber mounted 95 laterally of the fire-chamber, an apertured flue-head mounted on the smoke-chamber, a series of uptake-flues mounted on the flue-head above the flame-chamber, a series of 100 downtake-flues mounted on the flue-head above the smoke-chamber, and means for connecting the upper ends of the uptake and downtake flues, the smoke-chamber provided with an outlet, the products of combustion passing directly through the smoke-chamber 105 to the outlet irrespective of the flues or by passing through the entire lengths of both uptake and downtake flues.

6. The combination in a heater provided with a combustion-chamber, of a smoke-chamber mounted laterally thereof upon the stove, a flue-head removably supported on the smoke-chamber, a series of downtake-flues removably mounted upon the head, a series of uptake-flues removably mounted 115 above and in direct communication with the combustion-chamber, means for connecting the upper ends of the flues, the smoke-chamber provided with an outlet, a guard-ledge mounted on the flue-head, the guard-ledge 120 passing around the stove, and an extension of the ledge passing around the outlet-pipe to protect the same.

7. The combination with a stove provided with a combustion-chamber, of a flame-chamber located above and in communica-

tion therewith, a smoke-chamber located laterally of the flame-chamber, an outlet-pipe on the smoke-chamber and a pipe extending to and communicating with the combustion-chamber, means for controlling the communication with the combustion-chamber, and means for indirectly connecting the flame-chamber and smoke-chamber, the products

of combustion adapted to pass entirely through such indirect connecting means. ¹⁰

Signed at Mansfield this 20th day of February, 1904.
